UNITED STATES PATENT OFFICE.

DAVID SEGAL, OF WASHINGTON, DISTRICT OF COLUMBIA. ASSIGNOR OF ONE-HALF TO
JACOB SEGAL, OF LONG ISLAND CITY, NEW YORK.

FLYING-MACHINE.

1,036,732.

Specification of Letters Patent. Patented Aug. 27, 1912.

Application filed December 19, 1911. Serial No. 666,688.

To all whom it may concern:

Be it known that I, DAVID SEGAL, a citizen of the United States, residing at Washington, District of Columbia, have invented certain new and useful Improvements in Flying-Machines, of which the following is a specification.

This invention relates to flying machines.

It is now stated that the salient feature 10 of my invention is to provide means for correcting the tendency of the machine to tilt to an excess degree and for restoring the equilibrium of the machine when the latter is in flight without the provision of 15 mechanism for the collective and simultaneous control of the balancing planes, rudders or other movable parts of the machine which must only be disturbed with the utmost care, and to provide such means that 20 can be applied to any well known machine without necessitating elaborate changes in the construction thereof; further the provision of such means which will include a suspended weight beneath the gliding surface 25 face of the machine on a rigid sliding support which can be extended perpendicularly beneath the gliding surface to effect relative adjustments of the latter and the weight whereby it can be extended to any desired 30 position according to the pitch of the machine from its correct gliding position.

Another object of the invention is to provide such stability mechanism which, when adjusted to an inoperative position, will be 35 wholly out of contacting proximity with the surface of the ground during the landing or launching of the flying machine.

In the drawings, forming a portion of this specification and in which like numerals 40 of reference indicate similar parts in the several views:—Figure 1 is a transverse section through a biplane showing my invention applied thereto, parts being shown in full lines and the weight in its maximum uppermost position. Fig. 2 is a front view 45 of the same. Fig. 3 is a longitudinal section through the driving shaft showing the companion clutch elements thereon. Fig. 4 is a section on line 4—4 of Fig. 1. Fig. 5 is a section on line 5—5 of Fig. 1. Fig. 6 is a diagrammatic view of the flying machine illustrating the weight in maximum 50 lowermost position, illustrating in dotted

lines the tilted position of the machine and the initial position of the weight. Fig. 7 is 55 a perspective view of the weight control.

It is now stated that my stabilizer is designed for use upon any well known form of flying machine of the heavier or lighter-than-air type and only with a view of 60 clearly illustrating the invention has the same been embodied with the biplane structure 1 herein shown. This structure is shown to include the upper and lower planes or gliding surfaces 2 and 3 which are connected by the usual stanchions or uprights 4, the motor base or platform 5, the motor 6, and the propeller or driving shaft 7 and its propeller 8.

The stabilizer comprises a rigid support 70 or bar 9 which extends perpendicular to the plane of the gliding surfaces of the machine and is mounted to slide in fixed guides 10 on the frame of the machine in line with the center of gravity. This support has fixedly 75 connected thereto at its lower end a weight 11, which is preferably spherical so as to offer little resistance to the travel of the machine, the said weight being located beneath the lower plane or gliding surface 3 80 and it is adjustable with relation thereto in a manner hereinafter described. The weight support 9 is provided with a longitudinal series of transversely arranged teeth 12 which are adapted for intermeshing 85 engagement with the driven gear wheel 13 on the countershaft 14.

The countershaft is mounted in suitable bearing brackets 15 which rise from the base 5 and fixedly mounted on said shaft are 90 the driven pulleys 16 and 17, the former being connected by the crossed belt 18 to the pulley-like idle clutch element 19 on the driving shaft 7. The pulley 17 is connected by the belt 20 with the pulley-like idle 95 clutch element 21 on the driving shaft. The belt 20 has parallel leads, and the connection of the belt with the pulley 21 permits the countershaft 14 to rotate in an opposite movement to that imparted thereto through 100 the crossed belt 18. The elements 19 and 21 are provided with conical friction surfaces 22 against which the similar surfaces 23 on the clutch element 24 are adapted to engage according to the direction of movement 105 desired of the countershaft. The element 24

has secured thereto a key 25 which extends into the longitudinal keyway 26 in the driving shaft whereby movement will be constantly transmitted to the element. The 5 element 24 has an annular groove 27 therein to receive the collar 28 on the shift lever 29. The extensile springs 30 which are interposed between the elements 24, 19 and 21 serve to hold the element 24 in neutral position. It is now clear that means are employed for effecting the instantaneous rotation of the countershaft in either direction so that the bar 9 can be made to climb or fall as the occasion may demand. 10 The shift lever 29 supports a fixed pin having oppositely extending portions 31 and 32, the portion 31 being extended through the elongated slot 33 in the link 34 and the portion 32 being extended through a similar 20 but oppositely extending slot 35 in the link 36. A rock arm 37 is mounted in a suitable bracket 38 upon the frame of the flying machine, and as shown, the lower end of said arm carries a pin 39 to which the lower and 25 rear end of the link 34 is pivoted. The upper end of said rock arm has pivoted thereto, at 40, the upper end of the link 36. The links 34 and 36, and the actuating member 41 and control lever 42 form the means 30 for shifting the clutch element 24 to operative and inoperative positions.

The actuating member 41 has fixed thereto the spaced pins 43 and 44 between which the support 9 is adapted to slide. Near the 35 lower end the support carries an operating member or cam 45 which is adapted to ride against the pin 43 on the maximum uppermost travel of the support and thereby move the actuating member 41 to impart rocking movement to the shift link 29, resulting in the neutral shift of the keyed clutch element 24. The support also has fixed thereto near its upper end a similar cam 46 which may engage the pin 44 to also cause the 40 neutral shift to be imparted to the element 24.

In order that the support 9 can be locked against sliding movement when the element 24 is in a neutral position, I provide a brake 50 shoe 47 which is secured to a stem 48. This stem is slidable in guide brackets 49 on the frame of the flying machine, and as shown, the stem has secured thereto a shoulder 50 against which one end of a helical extensile spring 51 bears, the opposite end of the spring being engaged against one of the guide brackets 49, whereby the shoe 47 is normally held in an applied position. The 55 shoe is substantially of U-configuration in cross section, as shown in Fig. 4 of the drawings, so as to provide spaced guide flanges 52 to embrace the sides of the support 9. The frictional engagement of the surface 53 of the brake shoe against the support 9 is sufficient to hold the support against sliding 60

movement. The rod 48 is pivotally connected to one end of a draft link 54, the opposite end of the link being pivotally mounted on the pin 39 of the rock arm 37, whereby on movement of the rock arm in one direction the brake shoe will be adjusted to a released position. 70

The motor 6 and the elements operated therethrough which include the countershaft 14 form means whereby the support 9 can be readily adjusted to an operative or an inoperative position. In order that the support 9 can be operated on failure of the motor 6 to work, I provide the countershaft 14 with a sprocket gear wheel 55 which is connected by the drive chain 56 to a similar sprocket gear wheel 57 on the shaft 58. The shaft 58 is supported in any suitable well known manner in the frame of the flying machine and at one end it is provided with a bevel-pinion 59 which meshes with a similar bevel-pinion 60 on the crank shaft 61. This crank shaft carries a suitable hand wheel 62 which is preferably located adjacent to the controlling lever 42 and the latter and the former are also disposed in controlling proximately to the aviators' seat. 80

The slots 33 and 35 are disposed in intersecting planes and on reference to Fig. 1 of the drawings it is seen that the pin 31 on the shift lever 29 engages against the walls of these slots at the inner ends thereof. Now it is stated that when moving the control lever 42 in the direction of the arrow *a* the actuating rod 41 will be controlled so as to cause the pin 31 to bear against the inner end of the slot 35 sufficiently to impart rocking movement to the rock arm 37. This causes the draft rod 54 to impart the necessary movements to the brake shoe 47 to cause the release of the latter from the support 9. Simultaneously with this action the link 29 will be shifted to cause the clutch element 24 to engage with the clutch element 21, the latter becoming a fixed part of the driving shaft 7 so that power will be transmitted to the countershaft 14 to cause the controlled descent of the weight. At the maximum lowering of the support 9 the cam 46 will be brought to bear against the pin 44 effecting a shift of the actuating rod 41 and also causing movement to be imparted to the shift link 29 to restore the driving clutch element to its neutral position. Reverse movement of the support 9 will bring the cam 45 into engagement with the pin 43 with the resultant neutral shift of the driving clutch element. 100

It is now thought that the essential features of the invention are sufficiently described to enable one in the art to clearly understand the invention together with the subsequent brief description of the operation of the invention. 105

The apparatus is adjusted previous to 110

the launching of the flying machine so as to sustain the weight 11 in an inoperative position beneath the lowermost gliding surface 3 of the machine. Should the machine tilt 5 to excess degree either longitudinally or laterally the controlling lever 42 is operated to throw the driving clutch element into the driven idle clutch element 21, whereby power is transmitted to the countershaft 14 10 to cause the rigid support 9 to lower. Any desired adjustment of this support can be made to effect the required leverage to restore the machine to equilibrium or perfect balance and a subsequent control of the lever 15 42 is made to cause the idle driven clutch element 19 to respond to the action of the driving clutch element, whereby the support 9 is made to climb to its set position.

While it is described that the weight is to 20 be lowered on excess tilt of the machine, it obviously appears that, at the discretion of the operator, the weight can be lowered as soon as the machine is in flight, whereupon, the tilt of the machine will be eliminated 25 and the machine maintained in constant equilibrium. The superimposed fixed guides 10 are so associated to receive the support 9 that the greatest possible leverage upon the machine is obtained, the lower guide being 30 substantially at the center of the machine so as to act as the main point of which may be termed the fulcrum of the support, whereby the latter most effectively resists those outside forces which cause the improper balance.

I claim:

1. A flying machine, a movable weight disposed beneath the gliding surface of the machine, means for controlling movements 40 of the weight, and automatically controlled means for holding the weight against movement.

2. A gliding surface, a weight movable with relation to said surface, and a weight 45 controlled brake for holding the weight against movement after the latter reaches a predetermined position with relation to the surface.

3. A gliding surface, a weight movable 50 perpendicular to the plane of the surface, automatically controlled means for holding the weight against movement after the same reaches a predetermined position, means for moving the weight, and a control operable 55 to first release the holding means and to then render the second means operative.

4. The combination with a flying machine and a driving motor therefor, of a stabilizer 60 comprising a movable member disposed perpendicular to the plane of the gliding surface of the machine and terminating at its lower end in a weight, and motor actuated means for positively moving the member to both operative and inoperative positions.

65 5. In a stabilizer for flying machines, a

machine having a gliding surface, a driving motor, a member supported by the machine and movable perpendicular to the plane of said surface and terminating in a weight beneath the said surface, motor controlled means for moving the member, and means for rendering the first means inoperative, said means being operable through movements of said member.

6. In a stabilizer for flying machines, a 75 machine having a gliding surface, a driving motor, a member supported by the machine and movable perpendicular to the plane of said surface and terminating in a weight beneath the said surface, motor controlled 80 means for moving the member, and means for rendering the first means inoperative, said means being operable through predetermined movements of said member.

7. A flying machine including a driving 85 motor therefor, a weight disposed perpendicular to the plane of the gliding surface of the machine and slidable with relation thereto, motor controlled means for effecting adjustments of the weight and including driving and driven clutch elements, and means operable by the weight for rendering the clutch elements inoperative.

8. A flying machine including a driving 90 motor therefor, a weight disposed in line 95 with the center of gravity of the machine, a perpendicular support slidably mounted on the machine and connected, with said weight, motor driven means geared to said support and operable to effect adjustment of the weight with relation to the gliding surface, and means operable on predetermined movements of the support for rendering the first means inoperative.

9. A flying machine, a weight located beneath the gliding surface of the machine, a rack member slidably supporting said weight, means for holding the member against sliding movement, a driving gear wheel constantly meshing with said member, means for releasing the first means, and means for operating said gear wheel on release of said first means to impart sliding movement to the member.

10. A flying machine, a driving shaft 115 thereon, a countershaft, clutch elements mounted for independent movements on the driving shaft, means between one of the elements and the countershaft for driving the latter in one direction, second means 120 connecting the other element with the counter-shaft to drive the latter in a reverse direction, a third clutch element, keyed for longitudinal movements on the driving shaft and operable for driving engagement 125 with either of the first clutch elements, means for adjusting the third element, a weight located beneath the gliding surface of the machine and movable only in a perpendicular plane, and adjusting means be- 130

tween the weight and the said countershaft for moving the former with relation to the gliding surface.

11. A flying machine, a driving shaft thereon, a countershaft, clutch elements mounted for independent movements on the driving shaft, means between one of the elements and the countershaft for driving the latter in one direction, second means connecting the other element with the countershaft to drive the latter in a reverse direction, a third clutch element keyed for longitudinal movements on the driving shaft and operable for driving engagement with either of the first clutch elements, means for adjusting the third element, a weight located beneath the gliding surface of the machine and movable only in a perpendicular plane, and gearing between the weight and the said countershaft.

12. A flying machine, a driven shaft thereon, means for driving the shaft, a weight located beneath the gliding surface of the machine, means for rendering the shaft operative, a rigid bar disposed perpendicular to the plane of the gliding surface and slidably mounted in the machine and attached to said weight, and a control for said second means operable on predetermined movements of the said bar.

13. A flying machine including a drive shaft and a driven shaft, idle clutch elements on said drive shaft, fixed means on said countershaft, second fixed means on said countershaft, an operative driving connection between one of the said idle elements and the first fixed means for driving the countershaft in one direction, a second operative connection between the other idle clutch element and the second fixed means to revolve the countershaft in a reverse direction, a sliding clutch element on the

driving shaft keyed to rotate therewith and operable to singly engage the idle clutch elements, a weight located beneath the gliding surface of the machine, and movable in a perpendicular plane thereto, a member supporting said weight and operable through the countershaft to effect adjustment of the weight relatively to the gliding surface, and means operable through the medium of said member for maintaining the keyed clutch element in neutral position.

14. A flying machine, a driven shaft supported thereon, a driving shaft, idle clutch elements on said driving shaft, a shifting clutch element keyed for longitudinal movement on said driving shaft, driving connections between the countershaft and the idle clutch elements, controlling means for a weight located beneath the gliding surface of the machine, weight lowering and lifting means between the countershaft and the weight for effecting adjustments of the latter with relation to the gliding surface, and means operating on the maximum descent and ascent of the weight for moving the shifting clutch element to a neutral position.

15. A flying machine, a weight located beneath the gliding surface of the machine, a slidable rigid connection for adjusting the weight with relation to said gliding surface, and an automatically controlled brake operating to engage the bar on the maximum descent or the maximum ascent thereof.

In testimony whereof I affix my signature in presence of two witnesses.

DAVID SEGAL.
